(57) **CLAIM**

The ornamental design for an adjustable bed as shown and described.

DESCRIPTION

FIG. 1 is a top, front and left side perspective view of an adjustable bed showing our new design;

FIG. 2 is a top, rear and right side perspective view thereof;

FIG. 3 is a front elevational view thereof;

FIG. 4 is a rear elevational view thereof;

FIG. 5 is a left side view thereof, the right side being a mirror image thereto;

FIG. 6 is a top plan view thereof;

FIG. 7 is a top, front and left side perspective view showing the adjustable bed with one side of the bed board in a first raised position;

FIG. 8 is a top, front and left side perspective view showing the adjustable bed with both sides of the bed board in the first raised position;

FIG. 9 is a top, front and left side perspective view showing the adjustable bed with both sides of the bed board in a second raised position;

FIG. 10 is a top, front and left side perspective view showing the adjustable bed with both sides of the bed board in a third raised position;

FIG. 11 is a top, front and left side perspective view showing the adjustable bed with one side of the bed board in the third raised position and the other side of the bed board in the second raised position;

(Continued)

FIG. 12 is a top, front and right side perspective view with one side of the bed board removed to show the internal structure of the adjustable bed;

FIG. 13 is a top, front and right side perspective view with one side of the bed board removed to show the internal structure of the adjustable bed in a raised position;

FIG. 14 is top, front and left side perspective view of FIG. 12;

FIG. 15 is a top, front and left side perspective view with both sides of the bed board removed to show the internal structure of the adjustable bed in another raised position; and,

FIG. 16 is a top, front and right side perspective view of FIG. 15.

The broken lines in the drawings illustrate portions of the adjustable bed which form no part of the claimed design.
